UNITED STATES PATENT OFFICE.

CHARLES GARBE, OF PARIS, FRANCE.

DISTRIBUTING-VALVE.

1,124,127.

Specification of Letters Patent.

Patented Jan. 5, 1915.

Application filed November 25, 1912. Serial No. 733,463.

To all whom it may concern:

Be it known that I, CHARLES GARBE, citizen of the French Republic, residing at Paris, Department of the Seine, in France, 5 have invented certain new and useful Improvements in and Relating to Distributing-Valves; and I do hereby declare the following to be a full, clear, and exact description of the invention, such as will enable others 10 skilled in the art to which it appertains to make and use the same.

The invention relates to a type of distributing valves for gas and steam engines, its chief feature being that it is highly gas 15 or steamtight and yet does not comprise any adjustable parts.

The movable part of the valve, which is driven in any suitable manner, comprises a certain number of blades arranged at right 20 angles to the direction of the passing gases and engaging with corresponding parallel partitions disposed in the valve casing. A tight joint is obtained owing to the multiplicity of fixed and movable blades yet without it being necessary to adjust the movable 25 part within the fixed part.

Similar characters of reference designate corresponding parts throughout the different figures of the drawings.

30 In the accompanying drawings: Figure 1 is a sectional view of a valve according to the invention and to which a rectilinear alternative motion is communicated. Fig. 2 is a section on line A—A of Fig. 1. Fig. 3 is a view of a continuously rotating valve. Fig. 4 is a section on line B—B of Fig. 3. Fig. 5 is a view of a valve which receives an alternating rotative motion. Fig. 6 is a section on line C—C of Fig. 5. Fig. 7 represents a modification of the invention. Fig. 8 is a section on line A—A of Fig. 7. Figs. 9 and 10 represent constructional details. Fig. 11 represents another modification.

45 The exhaust valve shown in Figs. 1 and 2 comprises a chamber 1 communicating on one side, with the cylinder through the port 2, and on the other side, with the exhaust, through the port 3. Several parallel partitions 4 are so arranged in the chamber 1 as 50 to divide it in a certain number of compartments; the partitions being separated from each other by means of spacing pieces 5 and the whole is held together by bolts 6 and nuts 7.

55 The blades 8 fixed on the movable part rest on the corresponding partitions 4.

These blades are also separated from each other by spacing pieces 9 and the whole held together by any suitable means. Blades and spacing pieces are mounted upon a head 10 60 sliding in a chamber 11. In the shut-off position, it forms a tight joint by abutting against the partitions 4 and also against the spacing piece 12 which stops its upward movement. The head 10 is integral with a 65 rod 13 which slides in a guide 14. The rod 13 receives an alternating rectilinear movement from an appropriate device, for instance, from a rotating cam which lifts intermittently a rod 24 and which communicates its movement to the rod 13 by means of the spring 25. The return or opening movement of the valve is obtained by means of a spring 26, one end of which rests on the guide 14 and the other, on a collar 27 70 integral with the rod 13.

Owing to the peculiar arrangement of the partitions 4 and the blades 8, the gases which would traverse the valve in its shut-off position, would have to travel along a 80 very narrow, long and sinuous path. Consequently these gases would expand and lose some time in passing from one compartment into the next one; it suffices therefore, to provide a sufficient number of compartments to insure a gastight joint during the necessary time, *i. e.* one revolution of the motor. It must be remarked that a more certain gastight joint will be obtained if, by an appropriate device or simply by applying steam pressure, some of the blades 8 are applied against the partitions 4. When the valve is in its open position so as to permit of the free passage of gases from port 2 to port 3, these gases traverse a wide and 95 straight opening and there is nothing to impede or delay their exhaust.

The blades 8 and the partitions 4 can be stamped out of sheet iron and those exposed to the hot gases will naturally be of greater 100 thickness.

On examining Fig. 1, it will be found that the partitions 4 are not flush with the outside of the steam chest 1 but extend beyond and form a certain number of ribs. 105 This arrangement is very advantageous, for it favors cooling, especially if the drawn-in air is compelled to travel over these ribs by means of a suitable piping.

The invention can be easily applied to a 110 continuously rotating valve. It then comprises a chamber 1, Figs. 3 and 4, in the

interior of which are arranged several partitions 4 extending to the exterior so as to form cooling ribs. The valve is mounted on a continuously rotating shaft 15, supported by bearings 22 and 23. The blades 8 are fixed on a squared part 19 of the shaft 15 and are separated by spacing pieces 9. In order to avoid leakages in the bearings, the steam-side part of the shaft 15 will be provided with packing rings.

10 The ports 2 and 3 of the chamber 1, communicate with the cylinder and the exhaust, respectively. The partitions 4 have openings in line with and of the same size as the ports while the blades 8 possess wider holes 16. The shaft 15 revolves at a suitable speed so as to produce the exhaust at the required moment, for instance, in the case of a four cycle motor, the said shaft will revolve at half the speed of the crankshaft.

15 20 The bearings 22 and 23 can also take the place of stops so as to keep the blades 8 within the spaces between the partitions 4 and prevent any contact thereof; the gas-tightness being obtained by means of the great number of compartments arranged in series. If, on the other hand, the bearings are not arranged so as to act as stops, the blades 8 will be pressed onto the partitions 25 30 35 4 by steam or gas pressure and their resistance to the passage of gases will be more efficient.

Figs. 5 and 6 represent a similar device but receiving an alternating circular movement. The movable part of the valve consists of blades 8 mounted on the shaft 15. These blades occupy only a part of the length of chamber 1 so as to be able to open ports 2 and 3. The shaft 15, pivoting on 40 a spindle 17 which is fixed on the cylinder in any suitable manner, is continuously rocked by means of a lever 18 and a rod 20.

Figs. 7 to 10 represent a modification of the invention in which one valve insures both admission and exhaust and is mounted directly on the cylinder. The valve shown in Figs. 7 and 8, comprises a chamber 1 forming a cylinder cover and flush with the water jacket 33. This chamber comprises 45 50 55 60 65 partitions 4 kept separated by spacing rings 5. The whole is fixed on the water jacket by means of bolts 6 and nuts 7. Ports 2 and 3 have been bored in the walls of the chamber 1, the former communicating with the interior of the cylinder 38 by a conduit 29 and the latter with the exhaust by tubing 42. Orifices 34 in line with ports 2 and 3 have been drilled in the partitions 4 as well as orifices 35, both being equidistant from the center but about 90° apart. The openings 35 serve for the admission of the gas mixture which comes from the carbureter through a pipe 43 and enters the cylinder by a conduit 28.

65 The movable part of the valve comprises

a shaft 15 turning freely in a bearing 22 and pivoted on a spindle 17 which screws at 41 into the cylinder head.

It is evident that the spindle 17 instead of being in the axis of the cylinder could 70 be parallel or slanting in reference to it.

Every one of the blades 8 is perforated at 16 and can thus open successively the openings 34 and 35 of the partitions 4.

The valve is driven by a worm wheel 30 75 mounted on shaft 15 and engaging with a worm 31 mounted on the secondary shaft 32. This shaft is mechanically connected to the crankshaft and is driven at half of its speed. In this manner, the movable part 80 of the valve uncovers successively the admission and exhaust orifices and insures, by itself, the complete distribution of the motor according to the four cycle principle. The distributing can be changed by varying the 85 size and angular distance of the openings 16, 34 and 35.

The use of this system of distribution permits of considerably simplifying the construction of the cylinder; consequently ribs 90 40 can be cast on the whole or on a part of the cylinder, said ribs extending into the interior of the water-jacket, increase the contact surface of metal and water and thus insure a better cooling of the cylinder and of 95 the piston.

Instead of arranging the spacing rings in the manner shown in Fig. 7 they could reach the edge of the blades as shown in Fig. 1, in the latter case, however, the rings 100 would have to be drilled in line with the orifices 16 of the blades 8.

The valve can also be made of one piece of metal in which slots have been milled or cut for the reception of the partitions of the 105 fixed part.

Instead of admitting and exhausting the charge through the same orifice, each blade 8 can be drilled in two points so that, there will be one orifice for the admission and one 110 for the exhaust. These two orifices will have to be at a certain angular distance just as it is in the case of the orifices 34 and 35 of the partitions 4.

Figs. 9 and 10 show two devices to impede 115 the progress of gases into the interior of the distributor. In the device shown in Fig. 9, the lowest blade 8 of the valve has been provided with any desired number of circular ribs 36 engaging circular slots in the 120 lower part 37 of the chamber of the valve. Thus a perfect gastightness is obtained. The same result could be obtained with the device shown in Fig. 10; in this case both the lowest blade 8 and the lower part 37 125 of the chamber are provided with similar circular slots into which fits a circular ring 39 so as to avoid leakage. The devices shown in Figs. 9 and 10 can, if necessary, be applied to more than one blade.

Fig. 11 represents yet another modification of the invention in the case it is applied to a rotary motor in which the crank-shaft is stationary and the cylinders rotate. 5 The explosive charge is admitted through the interior 50 of the crankshaft 46 which is provided with an orifice 49 communicating with an annular chamber 48 made in the crank casing 47. Said chamber 48 communicates with the valve casing by a pipe 43. The valve is driven at the same speed as the crankshaft for one port serves for both the admission and the exhaust; the driving being effected by means of conical 10 gears 44 and 45, rod 32 and gears 30 and 31. 15 It must be noted, however, that in the last case all the moving parts have a continuously rotating movement.

It is quite evident that the invention is 20 not limited to the devices represented in the drawings and that it may be applied to different types of distributors whether they are fixed to the cylinder itself or to its casting or whether they are designed for the 25 admission or the exhaust.

The invention greatly simplifies the construction of valves for it permits of the use of rough cut pieces which move freely in their corresponding slots and yet insure a 30 suitable gastightness.

I claim:

1. A distributing valve comprising coöperating relatively movable sets of spaced plates, the plates of one set adapted when 35 the valve is closed to extend into and fit loosely in the spaces formed by the plates of the second set to thereby form a sinuous path for the controlled medium.

2. A distributing valve comprising a set 40 of spaced movable plates and a set of co-operating spaced stationary plates, the plates of one set adapted to enter the spaces between the plates of the other set and to fit loosely therein to form a sinuous path for the controlled medium when the valve is in the 45 closed position.

3. A distributing valve comprising a set of spaced movable plates, a coöperating set of spaced stationary plates, the plates of one 50 set adapted to enter the spaces between the plates of the other set, and the plates of said stationary set adapted to protrude from the valve casing to facilitate cooling.

4. A distributing valve comprising two 55 sets of coöperating interlapping members adapted when the valve is in the closed position to fit loosely together to form a sinuous path for the controlled medium.

5. A distributing valve comprising two 60 sets of coöperating interlapping members adapted when the valve is in the closed position to form a sinuous path for the con-

trolled medium, and means associated with the adjacent faces of two of the interlapping members to increase the resistance offered to the gases in their passage through the valve. 65

6. A distributing valve comprising two sets of coöperating interlapping members adapted when the valve is in the closed position to form a sinuous path for the controlled medium, one of said members provided with a rib adapted to loosely engage in a groove provided in the face of an adjacent member to lengthen the path of the 70 gases through the valve and to increase the resistance offered to their passage therethrough. 75

7. A valve for combustion engines and like uses comprising sets of relatively movable interlapping, but non-contacting, lamellæ adapted by movement to one position to open a passage through the valve and by movement to another position to obstruct flow through the valve. 80

8. A valve comprising a set of stationary lamellæ provided with a series of port openings and serving as the port member of the valve, a valve member therefor comprising a set of relatively movable lamellæ alternating with the others and coöperating therewith without substantial contact to open and close the passage through said 85 openings. 90

9. A valve for combustion engines and like uses comprising a port member presenting a surface extended in a direction away from the combustion space, and a coöperating valve member having a correspondingly extending surface, the two surfaces being 95 out of substantial contact and affording sufficient frictional resistance to flow of fluid between them to confine the pressure within the engine. 100

10. A valve comprising a port member 105 comprising an alined series of annular ported disks; a shaft rotatable concentrically within the series and bearing an alined series of ported disks interlapping but not contacting with said annular disks, the port 110 openings in both series of disks being capable of registry.

11. A valve for combustion engines, comprising a ported member, including a series of lamellæ, a valve member including a series of interlapping lamellæ, the innermost lamellæ being of greater thickness than other lamellæ. 115

In testimony whereof I affix my signature, in presence of two witnesses.

CHARLES GARBE.
